CLAIM

The ornamental design for a booklight, as shown and described.

DESCRIPTION

FIG. 1 is a perspective view of a booklight, incorporating the new design;

FIG. 2 is a right side view of the booklight of FIG. 1, the left side view being a mirror image of the right side view;

FIG. 3 is a front view of the booklight of FIG. 1; and,
FIG. 4 is a top plan view of the booklight of FIG. 1.
